ANTIQUE CAR PLAYGROUND CLIMBER

Richard Rudy, Reedsville, Pa., assignor to
Kilgore Corporation, Toone, Tenn.

Filed Apr. 15, 1974, Ser. No. 461,239

Term of patent 14 years

Int. Cl. D21—03

U.S. CL. D34—5 H

FIG. 1

FIG. 2

FIG. 3

FIG. 1 is a perspective view of the antique car playground climber showing my new design;

FIG. 2 is a front elevational view thereof;

FIG. 3 is a rear elevational view thereof;

FIG. 4 is a side elevational view thereof; and

FIG. 5 is a top plan view thereof.

I claim:

The ornamental design for an antique car playground climber, as shown.
